UNITED STATES PATENT OFFICE.

WILLIAM M. SHEWRY, OF CHICAGO, ILLINOIS.

COLLAR.

1,014,527.

Specification of Letters Patent.

Patented Jan. 9, 1912.

Application filed April 8, 1910. Serial No. 554,152.

To all whom it may concern:

Be it known that I, WILLIAM M. SHEWRY, a citizen of the United States, residing at Chicago, county of Cook, State of Illinois, have invented a certain new and useful Improvement in Collars, and declare the following to be a full, clear, and exact description of the same, such as will enable others skilled in the art to which it pertains to make and use the same, reference being had to the accompanying drawings, which form a part of this specification.

My invention has for its object to produce a collar which may be secured at the back by simply moving it transversely of the stem of a button and without making it necessary to insert the button through the usual button hole in the collar.

A further object of my invention is to produce a collar which may be fastened in the back not only in the manner above described but also by slipping a portion thereof under a portion of the neck band or under a loop carried by the neck band or an adjacent portion of the shirt.

The various features of novelty whereby my invention is characterized will herein-after be pointed out with particularity in the claims; but for a full understanding of my invention and of its object and advantages, reference may be had to the following detailed description taken in connection with the accompanying drawing, wherein:

Figure 1 is a perspective view of a collar containing my improvements; Fig. 2 is a section taken on line 2—3 of Fig. 1 showing the manner of using the collar with a button; and Fig. 3 is a view similar to Fig. 2 showing the method of attaching the collar where no button is used.

Referring to the drawing, A represents a collar of any style or type. On the inside of the collar and at the back thereof are two tabs B. These tabs are fastened at their lower ends adjacent to the bottom of the collar and project upwardly on the inner side of the collar. The tabs are arranged close together, their adjacent edges even touching each other if desired; thereby forming a long upright slit or passage-way C between the same. The upper ends of the tabs are preferably rounded at the inner corners, as indicated at b so as to provide a flaring mouth at the upper end of the slit or passage.

In using the collar upon a shirt having the usual button or stud at the back, it is only necessary to bring the slit between the two tabs beneath and in alinement with the stem of the button or stud, indicated at D in Fig. 2, and then to push the collar up until the stem enters the slit. When the collar is fastened at the front in the usual way it cannot become disengaged at the back because it is prevented from dropping down by the body of the wearer. To move the collar it is simply unbuttoned at the front and is then withdrawn downwardly at the back.

In the preferred form of my invention the tabs are only secured adjacent to their lower ends, the body of the tabs being left free. This is for the purpose of permitting the tabs to be slipped under a portion of the neck band or a loop as indicated at E in Fig. 3; the neck band being indicated as E'. Thus the same collar may be secured in two different ways. However, if it is not desired to form the collar so that it may be secured by slipping a tab under a neck band or loop, the sides and even the upper edges of the tabs could be secured to the collar as this would not interfere with the ready engagement of the tabs with the button.

The two tabs may be formed in various ways, but I believe the best and cheapest way is to make them separate from each other and not out of the same piece because this permits them to be turned in at their adjacent edges and to be seamed; thereby making the adjacent edges stiff when starched and ironed so as to make the interlocking connection between the collar and the button firm and secure.

While I have illustrated and described with particularity only a single form of my invention I do not desire to be limited to the specific details so illustrated and described; but intend covering all constructions and arrangements which fall within the terms employed in the definitions of my invention in the appended claims.

I claim:

1. A collar having two independent tabs secured to the inner side at the back thereof, said tabs lying side by side with their adjacent edges close together, said tabs being secured only at their lower ends so as to form between them a slit open at the top.
2. A collar having two tabs secured at

their lower ends to the inner side at the back thereof, said tabs lying side by side with their adjacent edges close together so as to form between them a slit open at the top, 5 said adjacent edges gradually receding from each other adjacent to the top so as to form a mouth leading to the slit.

In testimony whereof, I sign this specification in the presence of two witnesses.

WILLIAM M. SHEWRY.
